UNITED STATES PATENT OFFICE

WILLIAM J. WOOLLEY, OF CHICAGO, ILLINOIS

VALVE FOR WATER CLOSETS

Application filed August 2, 1929. Serial No. 382,950.

This invention relates in general to valves, and has more particular reference to flush valves for water closet tanks.

A principal object of this invention is to provide a flush valve of a water closet tank with a plunger which makes a water-tight joint with the valve seat when the valve is closed.

Another important object of the invention is to provide a flush valve of a water closet tank with a plunger which has a portion of leather, or other treated fibrous material adapted to seal the valve port when the valve is closed.

Another important object of the invention is to provide a flush valve of a water closet tank with a plunger having a portion of leather, rubber, or other treated fibrous material which is reinforced to protect the leather or rubber against excessive packing and radial expansion of the plunger when the valve is operated, thereby causing leakage through the valve.

Another object of the invention is to provide a flush valve of a water closet with a plunger which is efficient and reliable in operation and which is simple and durable in construction.

Numerous other objects and advantages of the invention will be apparent as it is better understood from the following description, which, when taken in connection with the accompanying drawings, discloses a preferred embodiment thereof.

Referring to the drawings:

Figure 1 is an elevation of a water closet tank embodying the invention; and

Fig. 2 is a vertical section taken through the valve shown in Fig. 1.

For the purpose of illustrating the invention, the drawings show a usual water closet tank 11 provided with a feed pipe 12 adapted to be connected on one end to a suitable water supply, to extend into the tank and to communicate with a suitable feed control valve (not shown). A vertically disposed overflow pipe 13 is mounted in a bracket seat 14 which communicates with the pipe 13 and with a flush valve body 15 cast at one end of the bracket. The valve body 15 is cast to seat

on the bottom of the tank 11, in spaced relation with the bracket seat 14 of the overflow pipe 13, and provides a means for draining the tank 11. The valve body 15 is provided with a valve seat 16 which surrounds a port communicating at its lower end with a waste pipe 17 having suitable pipe connections to the bowl of the water closet.

A valve plunger 18, for closing the valve seat 16, has threaded engagement at 19 with the lower end of a valve stem 21. The valve stem 21 is adapted to be operated from a usual handle 22 positioned on the outside of the tank 11 and extending through a wall whereby to actuate the plunger 18 through suitable connections, not shown, and to open the valve in the flushing operation of the water closet.

The body of the valve plunger 18 is formed from a suitable material, such as hard rubber, to provide a head 23 having its upper portion dome-shaped and having a boss 24 formed substantially centrally of the dome-shaped portion and threaded as at 19 to receive the lower end of the stem 21. The head 23 has substantially vertical sides 24 depending from the dome portion and is provided near the lower end of the head with an inwardly extending flange 25 and with a depending flange or edge portion 30 extending below the flange 25 as a prolongation of the sides 24. The inwardly extending flange 25 provides a shoulder adjacent a vertically disposed skirt 26 which depends from the interior portion of the inwardly extending flange 25. The skirt 26 has an externally threaded portion 27 at its lower end to receive a cap 28 having interior threads 29 which co-operate with the threads 27 on the skirt 26 to hold the cap 28 on the end of the skirt 26. The closed end of the cap 28 extends below the threaded end of the skirt 26 as shown in Fig. 2, and is formed substantially as an inverted dome, the cap being adapted to be received through the valve seat 16 when the valve is closed.

The cap 28 is provided to hold a collar 31 of leather, rubber, or other suitable fibrous material on the skirt portion against the inwardly extending flange 25 of the head 23.

and between the skirt portion and the depending flange 30. The collar 31 is constructed of any suitable fibrous material, such as a suitably treated felt, rubber, or leather for valve packing, and is arranged to embrace the skirt portion 26 for the purpose of sealing the valve port by fitting the seat 16 of the valve 15 so that the cap 28 depends into the valve port. A metal washer 32 having a plurality of upstanding projections or teeth 33 around its periphery is of slightly larger diameter than the cap 28 and is adapted to embrace the skirt 26 between the cap 28 and the fibre collar 31, so that the teeth 33 are in engagement with the fibre collar. The washer 32 is provided with the teeth 33 for the purpose of reinforcing the fibre collar 31 to prevent excessive packing of the collar and for co-operating with the depending flange 30 to prevent excessive radial expansion due to packing in the operation of the valve.

In operation the plunger 18 is raised by rotating the handle 22 to open the valve 15 and to flush the water closet, which opens the feed control valve in a usual manner and permits refilling of the tank through the feed pipe 12, when the plunger 18 has been reseated in the valve port of the valve 15. Repeated operations of the valve 15 will tend to pack the fibrous material of the collar 31, but the teeth 33 of the washer 32 and the depending flange 30 of the head 23 will prevent excessive radial expansion of the collar and consequent leakage around the plunger.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A valve plunger for flush valves of water closet tanks, comprising a body having an enlarged head and a skirt depending therefrom, a cap adapted to threadably engage the end of said skirt, a fibre collar arranged to embrace said skirt between said head and said cap for sealing the valve port, and reinforcing means arranged to embrace said skirt adjacent said cap to prevent leakage around said collar due to packing and radial expansion in the operation of the valve, said means being adapted to frictionally engage said collar.
2. A valve plunger for flush valves of water closet tanks, comprising a body having an enlarged head and a skirt depending therefrom, a cap adapted to threadably engage the end of said skirt, a fibre collar arranged to embrace said skirt between said head and

said cap for sealing the valve port, and a metal washer arranged to embrace said skirt adjacent said cap and having a plurality of teeth arranged to project upwardly and to engage the fibre collar to prevent leakage around said collar due to packing and radial expansion in the operation of the valve.

WM. J. WOOLLEY.
